(57) **CLAIM**

The ornamental design for a cart for a water jetting machine, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise re-serves all copyright and trade dress rights whatsoever. FIG. 1 is a perspective view of a cart for a water jetting machine.

FIG. 2 is a front elevation of a cart for a water jetting machine.

FIG. 3 is a rear elevation of a cart for a water jetting machine.

FIG. 4 is a left side elevation of a cart for a water jetting machine.

FIG. 5 is a right side elevation of a cart for a water jetting machine.

FIG. 6 is a bottom view of a cart for a water jetting machine; and,

FIG. 7 is a top view of a cart for a water jetting machine. The broken lines shown in the figures are for the purpose of illustrating portions of the cart for a water jetting machine and form no part of the claimed design.
